(57) CLAIM

I claim the ornamental design for a shoe sole, as shown and described.

DESCRIPTION

FIG. 1 is a bottom plan view of a shoe sole showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a cross sectional view taken on line 6—6 of FIG. 1;

FIG. 7 is a cross sectional view taken on line 7—7 of FIG. 1; and,

FIG. 8 is a cross sectional view taken on line 8—8 of FIG. 1.

The broken line showing a shoe upper FIGS. 2—5, and the interior surfaces in FIGS. 6—8, illustrate portions of the design that form no part of the claim.
